United States Patent Office

Des. 193,757
Patented Oct. 2, 1962

193,757

FAUCET

William H. Armstrong, Birmingham, Mich., assignor to
Borg-Warner Corporation, Chicago, Ill., a corporation
of Illinois

Filed Apr. 4, 1962, Ser. No. 69,573

Term of patent 14 years

(Cl. D91—3)

Fig. 1

Fig. 2

Fig. 4

Fig. 3

FIG. 1 is an isometric view of a faucet, showing my new design;

FIG. 2 is a top plan view thereof;

FIG. 3 is a front elevation thereof;

FIG. 4 is a side elevation thereof.

I claim:

The ornamental design for a faucet, substantially as shown.
